UNITED STATES PATENT OFFICE.

CHARLES FREDERICK DICKSON, OF LONDON, ENGLAND, ASSIGNEE, BY MESNE ASSIGNMENTS, TO CHARLES GOLD, OF RAVENS, STANSTED, ENGLAND.

ADVERTISING DEVICE.

Application filed September 15, 1925, Serial No. 56,543, and in Great Britain August 21, 1925.

This invention has for its object to provide a method whereby an illuminated advertisement can be made to appear in the windscreens of automobile vehicles. It has 5 a further object to provide an illuminated sign in combination with said windscreens and arranged at such an angle that the sign can be viewed forwardly of the automobile by reflection in said windscreens.

10 The invention is illustrated in the accompanying drawing in which:—

Fig. 1 illustrates part of a commercial vehicle fitted with a hood.

Fig. 2 part of a pleasure or touring car.

15 Fig. 3 shows a modification of Fig. 1, and Fig. 4 a modification of Fig. 2.

Referring now to the drawing, the automobile 1, Fig. 1, is provided with a rigid hood 2 surmounting the driver's seat, the 20 windscreens 3 of glass or other transparent material being mounted in front of the driver as shown. According to the invention I mount on the underside of the hood a sign 4 adapted to be illuminated and arranged in such a manner that it may be viewed from a point in front of the vehicle as indicated by the line 5 representing a ray of light. A screen 6 is provided rearwardly 25 of the sign 4 to prevent it from being directly viewed by the driver.

It will of course be appreciated that the observer in front of the vehicle will see an image of the sign 4 appearing to be located in the middle of the windscreens thus producing a novel advertising effect without, however, in any way embarrassing the driver of the vehicle, who of course will have his usual clear field of view through the windscreens uninterrupted.

30 Fig. 2 shows the invention as applied to a touring car in which the sign 4 is adapted to be held by a frame 7 comprising hinged arms 5 mounted to the brackets supporting the windscreens 3. Alternatively, the sign 4 can be supported by a frame such as shown 35 in dotted lines at 8 carried from the foot boards of the vehicle.

In these modifications the illuminated face of the sign 4 is directed rearwardly and 40 downwardly.

Turning now to Fig. 3 the sign 4 in this modification is directed forwardly of the vehicle, and is made visible in the manner described by means of a rearwardly directed 45 mirror 9 mounted in front of the sign, the

mirror 9 being angularly adjustable about a hinge 10 preferably carried by a plate 11, preventing direct vision of the sign 4 by a person situated at any distance in front of the vehicle and adapted to permit of the 60 windscreens 3 having various settings without interfering with the general location of the area from which the sign can be viewed in front of the vehicle.

It will be appreciated that within suitable 65 limits by tilting the mirror 9 the reflected beam of light 5 can be maintained horizontal whatever the angular setting of the windscreens 3.

Fig. 4 shows a modification employing a 70 rearwardly directed mirror 9 as applied to a touring car. In this modification the sign 4 is mounted on the top of the bonnet of the car with its face directed upwardly, and the ray of light 5 passes obliquely forwards on 75 to the mirror 9 thence rearwardly on to the windscreens 3 and then forwardly and horizontally as before.

It will be appreciated that in all forms 80 the sign itself is not visible to the observer whose eye is reached by the beam 5, direct view of the sign of Fig. 3 being obstructed by the plate 11.

Preferably, the sign is electrical and may 85 be governed by means causing it to flash and become extinct at alternate short periods.

While I have illustrated the beam 5 which falls more or less on the centre of the windscreens as reflected horizontally therefrom, it is to be understood that this is only by way 90 of example, as it can be projected so as to fall slightly above or below the horizontal, in the latter case reaching the ground a considerable distance in front of the vehicle. Obviously beams reaching the windscreens at 95 points lower than and higher than that illustrated will render the sign visible at points below and above the illustrated reflected beam 5.

It will be observed that in all forms the 100 sign or mirror is so arranged as to lie on a plane intersecting the windscreens along a horizontal line intermediate its height and making an angle with the adjacent part of the windscreens substantially equal to the inclination of the windscreens to the horizontal.

I claim:—

1. In an automobile, a windscreens, a sign 105 located in front of the said windscreens and lying on a plane which intersects along a 110

horizontal line the windscreens intermediate its height and makes with it an angle substantially equal to the inclination of the windscreens to the horizontal.

5. 2. In an automobile, a windscreens, a sign located in front of said windscreens and a mirror, the mirror being arranged forwardly of the windscreens and lying on a plane which

intersects along a horizontal line the windscreens intermediate its height and makes with it an angle substantially equal to the inclination of the windscreens to the horizontal. 10

In testimony whereof I affix my signature.

CHARLES FREDERICK DICKSON.
